LAVATORY HANGER

James R. Beam, New Castle, Pa., assignor to Universal-Rundle Corporation, New Castle, Pa., a corporation of Delaware

Application July 14, 1949, Serial No. 104,759

9 Claims. (Cl. 4—170)

1

This invention relates to lavatories or stationary wash basins which are used in bathrooms, and more particularly, to means for securing such lavatories to a bathroom wall. The invention is especially useful in its application to vitreous china lavatories, to which use, however, it is not restricted.

Various methods are employed for supporting a lavatory or stationary wash basin in convenient position in a bathroom and at the correct elevation above the bathroom floor. One method is to hang the lavatory in appropriate position from a suitable wall.

Heretofore, lavatories have been hung from bathroom walls by means of brackets or the like which are fixed to the wall and project therefrom. A simple hanger or bracket is formed as a central portion for attachment in horizontal position upon the wall, the central portion having an outwardly turned longitudinal flange over which a rearward flange of the lavatory is placed to position the lavatory upon and against the wall. Because of the closely textured surface of vitreous china and enameled metal, the flange of the lavatory does not grip the hanger; and the lavatory is likely to move from its snug fit against the wall, to work loose from the wall and either to drop to the floor or be suspended by the plumbing system alone. It is, therefore, necessary to provide means for holding the lavatory down upon the hanger. In the past such means has been complicated or inflexible, requiring close fitting of the parts. Where bolts or screws have been employed in order to hold the lavatory down upon the hanger, there has been a tendency, in fitting out the bathroom, not to apply such bolts or screws in sufficient number to accomplish their purpose.

According to the present invention, a simple hold-down hanger is provided, preferably in unitary form, which is very simply attached to the lavatory, when in place thereon, to hold it down upon the hanger. Register of apertures or holes in the hold-down hanger and in the lavatory need not be exact, and the hanger is constructed to coat with a variety of lavatories.

The invention is illustrated by way of example in the following drawings, in which—

Fig. 1 is a perspective view of a hold-down hanger constructed in accordance with the invention;

Fig. 2 is a top plan view of the hanger illustrated in Fig. 1;

Fig. 3 shows the same hanger as viewed from the right in Fig. 2;

2

Fig. 4 is an elevation of the same hanger;

Fig. 5 illustrates the hanger as seen in Fig. 2, on a reduced scale, showing in phantom view a standard lavatory applied thereto;

Fig. 6 is a view of the hanger as seen in Fig. 4 showing the hanger assembled with a lavatory illustrated in phantom form;

Fig. 7 is a mid-section through the same hanger and a lavatory carried thereby and held down thereon; and

Fig. 8 is an enlarged broken fragmental view illustrating the method of holding the lavatory down upon the hanger.

The drawings show a hold-down hanger 10 and a lavatory 11, which the hanger is constructed to support upon a wall 12 or upon a suitable block fixed to the wall. Means is provided for holding the lavatory down upon the hanger when supported by the latter, as will later be explained.

The hanger 10 is preferably formed from a unitary metal strip and comprises a central portion 13 and integral side portions 14 and 15 which are turned outwardly and downwardly from the central portion 13. The side portion 14 has an end 16 turned outwardly thereof, and the side portion 15 has a similar end 17 turned outwardly thereof. Preferably, the side portions 14 and 15 lie in planes which are perpendicular to the central portion 13, and the outwardly turned ends 16 and 17 are coplanar, the plane in which they lie being perpendicular both to the plane of the central portion 13 and the respective planes of the side portions 14 and 15. See Fig. 1.

A longitudinal flange 18 is turned outwardly from the top of the central portion 13 and serves to give immediate support to the lavatory 11 and to hold the latter snugly against the wall 12, as will later be explained. It will be obvious that the hold-down hanger 10 may be stamped or cut from a single strip of material and bent into the form illustrated. At the time of forming the hanger, a series of perforations 19 may be pierced through its central portion 13 to accommodate screws or the like for attaching the hanger to the wall. It is preferred to provide a considerable number of such perforations and to position them longitudinally of the central portion 13 in two rows, vertically spaced and staggered, in order to insure adequate supporting connection with the wall. It is thus possible, as where metal studding in the wall is encountered behind the hold-down hanger, to employ sufficient screws or the like to support the hanger firmly upon the wall. Furthermore, the double row of perforations provides additional opportunity for secur-

ing the hanger to the wall and additional stability of the connection.

Each of the outwardly-turned ends 16 and 17 has a hole 20 punched therethrough for accommodation of a hold-down bolt, later to be described. Since the side portions 14 and 15 are turned outwardly and downwardly from the central portion 13, the outwardly-turned ends 16 and 17 are carried below the longitudinal flange 18 upon which the lavatory is hung. By suitably proportioning the side portions and the end portions, the holds 20 may be positioned in desirable location beneath the lavatory 11.

The lavatory itself is of standard form and need not be described in detail. It is to be noted, however, that at the rear of the lavatory 11 a downwardly projecting flange 21 is provided which extends transversely of the lavatory and substantially horizontally. Thus the flange 21 may be hooked over the longitudinal flange 18 of the hanger 10 to support the lavatory upon the wall 12. The flange 21 is preferably of wedge-shaped section, as best shown in Fig. 7, and fits snugly behind the longitudinal flange 18 of the hanger along which it slides tightly against the wall 12.

In order that the lavatory may be held down firmly upon the hanger with the downwardly-projecting flange 21 of the former securely wedged between the longitudinal flange 18 of the latter and the wall 12, special means is provided for coaction between the lavatory and the hanger. Accordingly, the lavatory is provided with lower side flanges 22 and 23 lying substantially horizontally above the positions of the ends 16 and 17, respectively, of the hanger when the latter is fixed to the wall and the lavatory is hung thereon. As illustrated in Figs. 6, 7 and 8, these side flanges comprise the bottom walls of completely enclosed chambers formed in the lavatory. However, it is not necessary that the lower side flanges 22 and 23 be so formed.

The lower side flanges 22 and 23 of the lavatory have openings formed therein, as the opening 24 in the flange 23. These openings are formed substantially coaxially with the holes 20 in the respective ends 16 and 17 of the hold-down hanger with the lavatory and the hanger in their positions when secured to the wall 12.

In order to hold the lavatory down upon the hanger 10 with the downwardly projecting flange 21 of the lavatory snugly in place against the longitudinal flange 18 of the hanger and against the wall 12, a bolt 25 is passed upwardly through each of the holes 20 and through the corresponding opening in the adjacent lower side flange of the lavatory. A toggle nut 26 of well-known construction is threaded upon each bolt 25 and is thrust upwardly through the opening in each of the side flanges by the bolt 25 upon which it is threaded. See Fig. 8. Upon passing through the opening in the lower side flange, the toggle bolt 26 opens in well-known manner and bears upon the upper side of the flange as the bolt is tightened. See Fig. 6. A washer 27 positioned between the head of each bolt 25 and the hole 20 through which it extends, functions in the usual manner between the bolt head and the end of the hold-down hanger.

Thus, each bolt 25 may be turned to tighten the connection between the hanger end through which it passes and the adjacent lower side flange of the lavatory, the toggle nut bearing against the inside of the lower side flange as the bolt is turned through it. By making the hold-down

hanger of resilient material, as sheet steel, a certain resiliency of connection between the hold-down hanger and the lavatory may be effected.

From the foregoing it will be evident that the invention provides simple and effective means for supporting a lavatory upon a wall and for holding the lavatory securely upon its support. Accurate fitting and register of parts is not required. For example, the opening 24 need not be precisely coaxial with the hole 20 in the end 17 of the hanger. Slight variations are easily compensated for by the flexibility of the toggle nut and slight angular movement of the bolt 25 with respect to the hole 20. Furthermore, the hold-down hanger 10 is of exceedingly simple construction and may be easily and inexpensively produced.

The form of the invention herein described and illustrated is presented merely as an example of how the invention may be applied. Other forms and embodiments of the invention coming within the proper scope of the appended claims will readily suggest themselves to those skilled in the art.

I claim:

1. A hold-down hanger for a lavatory or the like comprising a central portion, and integral side portions turned outwardly and downwardly from each end of said central portion, each of said side portions having an end turned outwardly thereof, said central portion being perforated to accommodate screws or the like for attaching the hanger to a wall and having an upper outwardly-turned longitudinal flange for hanging a lavatory or the like thereon, and the end of each of said side portions having a hole therein through which a bolt may project for holding the lavatory or the like down upon the hanger.

2. A hold-down hanger for a lavatory or the like comprising a substantially flat central portion, and integral flat side portions turned outwardly and downwardly from each end of said central portion substantially at right angles thereto, each of said side portions having an end turned outwardly thereof substantially at right angles to said side portions and to said central portion, said central portion being perforated to accommodate screws or the like for attaching the hanger to a wall and having an upper outwardly-turned longitudinal flange for hanging a lavatory or the like thereon, and the end of each of said side portions having a hole therein through which a bolt may project for holding the lavatory or the like down upon the hanger.

3. A hold-down hanger for a lavatory or the like formed from a strip of resilient material and comprising a central portion, and integral side portions turned outwardly and downwardly from each end of said central portion, each of said side portions having an end turned outwardly thereof, said central portion being perforated to accommodate screws or the like for attaching the hanger to a wall and having an upper outwardly-turned longitudinal flange for hanging a lavatory or the like thereon, and the end of each of said side portions having a hole therein through which a bolt may project for holding the lavatory or the like resiliently down upon the hanger.

4. A lavatory hanger comprising an elongated central portion for attachment in horizontal position to a wall, said central portion having its upper edge bent outwardly to permit a lavatory

to be hung over its top; a resilient arm downwardly and outwardly extending from each end of said portion; and a tightening element for connecting each of said arms with the lavatory, whereby the lavatory may be resiliently held down upon said hanger.

5. A lavatory hanger comprising an elongated central portion for attachment in horizontal position to a wall, said central portion having its upper edge bent outwardly to permit a lavatory to be hung over its top; a resilient arm downwardly and outwardly extending from each end of said portion, the ends of said arms being turned outwardly thereof and having holes therein; and bolts projecting through the holes in the ends of said arms for coacting with nuts in the lavatory, whereby the lavatory may be resiliently held down upon said hanger.

6. A lavatory hanger comprising an elongated central portion for attachment in horizontal position to a wall, said central portion having its upper edge bent outwardly to permit a lavatory to be hung over its top; a resilient arm downwardly and outwardly extending from each end of said portion; the ends of said arms being turned outwardly thereof and having holes therein; bolts projecting through the holes in the ends of said arms; and toggle nuts threaded upon said bolts for passing through openings in the lavatory and expanding, whereby tightening said bolts in said toggle nuts will resiliently hold the lavatory down upon said hanger.

7. In combination, a lavatory and means for supporting said lavatory upon a wall in operative position; said lavatory having a rear, transverse, downwardly-projecting flange, and substantially horizontal lower side flanges each having a hole therein; said supporting means comprising a central portion being perforated to receive screws or the like for attaching said portion to the wall, and having an outwardly projecting upper longitudinal flange for receiving the rear flange of said lavatory when said portion is fixed horizontally to the wall with its longitudinal flange extending upwardly away from the wall; side portions turned outwardly and downwardly from each end of said central portion; end portions extending outwardly from said side portions substantially at right angles thereto, said end portions extending beneath the lower side flanges of said lavatory and each having a hole therein positioned to lie beneath the hole in a side flange of said lavatory; bolts having heads larger than the holes in said end portions extending through such holes and through the corresponding holes in the lower flanges of said lavatory; and nuts threaded on said bolts on the opposite sides of the lavatory openings and of the holes in said end portions from the heads of said bolts, whereby tightening

said nuts upon said bolts will pull said lavatory downwardly upon the hold-down hanger by a force opposite to the supporting force of the longitudinal flange on said central portion.

8. In combination, a lavatory, and means for supporting said lavatory upon a wall in operative position; said lavatory having a rear, transverse, downwardly-projecting flange of wedge-shaped section, and substantially horizontal lower side flanges each having a hole therein; and said supporting means comprising a central strip-like portion having an outwardly-projecting upper longitudinal flange for receiving the lower part of the rear flange of said lavatory when said portion is fixed horizontally to the wall with its longitudinal flange extending upwardly away from the wall, said portion being perforated to receive screws or the like for attaching said portion to the wall; integral flat side portions turned outwardly and downwardly from each end of said central portion substantially at right angles thereto; integral end portions extending outwardly from said side portions substantially at right angles thereto and substantially at right angles to said central portion, said end portions extending beneath the lower side flanges of said lavatory, each of said end portions having a hole therein beneath the hole in a side flange of said lavatory; bolts projecting through the holes in said end portions and through the corresponding holes in the lower side flanges of said lavatory; and nuts on said bolts for urging said lavatory down upon said supporting means.

9. A lavatory hanger comprising an elongated portion for attachment in horizontal position to a wall, said portion having its upper edge bent outwardly to permit a lavatory to be hung over its top; a resilient arm downwardly and outwardly extending from said elongated portion; and a tightening element for connecting said arm with the lavatory, whereby the lavatory may be resiliently held down upon said hanger.
